LANTERN

Filed Oct. 13, 1926

INVENTOR.
John J. Ramsey
BY
E.G. Charles
ATTORNEY.

UNITED STATES PATENT OFFICE.

JOHN J. RAMSEY, OF WICHITA, KANSAS.

LANTERN.

Application filed October 13, 1926. Serial No. 141,316.

My invention relates to improvements in lanterns.

The object of my invention is to provide a lantern utilizing a fruit jar or the like in which is placed a candle or fuel oil container, the said container having a wick as a lighting element.

A further object of my invention is to provide a tube having a wick extending therethrough and the fuel oil placed in the fruit jar.

A still further object of my invention is to provide a lantern that will function as a smudge pot.

15 A still further object of my invention is to provide a lantern that may be placed concentrically in a fluid container as an insect exterminator.

These and other objects will hereinafter 20 be more fully explained.

Referring to the drawings;

Fig. 1 is an elevation of the mechanism.

Fig. 2 is a plan view of Fig. 1.

25 Fig. 3 is a cross sectional view taken on line III—III in Fig. 1.

Fig. 4 is an elevation of the mechanism embodying certain modifications hereinafter described.

Fig. 5 is a plan view of Fig. 4.

30 Fig. 6 is another modification of the mechanism.

Fig. 7 is a plan view of Fig. 6.

The mechanism herein disclosed consists of a fruit jar 1, which is preferably used to illustrate the device in combination with other elements, the said jar having the usual type of lid 2 threadedly engaging on the top thereof, the center of the lid is removed providing an aperture to receive a chimney 3, the said chimney extending downward into the jar has a yoke 4 attached thereto, pendently supporting a socket 5 in which the end of a candle 6 may be placed, the opposite end of the chimney is covered with a hood 7 by means of fingers 8 snugly engaging thereon, the said hood being spaced a short distance from the chimney so that the heated air from the flame of the candle will pass out freely and as a means for circulation 45

50 I have provided a plurality of openings 9 about the periphery of the aperture through the can lid as shown in Fig. 7, through which the air will drop downward supplying oxygen for the flame, as a guard or shelter 55 for the openings I have placed a flange 10

flaring outward to extend thereover, the said flange being rigidly attached to the chimney.

It will be understood that the chimney will fit snugly in the aperture of the lid and may be soldered or otherwise firmly attached thereto functioning as a carrying means for the jar through the medium of a bail 11 pivotally engaging in the wall of said chimney as at A. When placing a candle or lighting the same, the glass jar is removed by unscrewing the lid therefrom carrying with it the yoke and other parts connected therewith. It is now readily seen how the light is sheltered from the outside current so that it will not become extinguished as 70 the jar is a transparent, solid enclosure.

The modification of the chimney and the fuel container shown in Fig. 1 function in like manner so far as air circulation and the light is concerned, that is to say the 75 corrugated chimney provides an inlet through the corrugations extending inward, there being an opening through the lid by reason of the aperture through said lid being round, the light is produced by the medium 80 of a wick extending through a tube 12 with the opposite end being immersed in fuel oil placed in the container 13 carried by a similar yoke and secured therein by a band 14 attached to said yoke.

The modification as shown in Fig. 6 is 85 similar to that of Fig. 1 except that the fuel oil is placed in the jar and a tube 15 attached to the yoke extends downward near the bottom of the jar having a wick 16 slideably engaging therein and by capillary attraction the oil is fed upward to the lighting point. When the lantern herein disclosed is used as an insect exterminator a pan 17 is partially filled with fluid and the lantern 90 placed concentrically therein, the fluid may be crude oil or the like or it may be water with a light coating of oil, so that the insects attracted by the light when contacting the jar will gradually work downward, dropping into the fluid.

95 Such modifications may be employed as lie within the scope of the appended claims.

What I claim as new and desire to secure by Letters Patent is:

100 1. In a lantern, in combination with a transparent jar, an apertured lid threadedly engaging on the top of the jar, of a chimney engaging through the aperture in axial alignment with the jar, a plurality of open- 105

ings through the top of the lid about the periphery of the chimney as circulating means while the heated air is passing out of the chimney, a hood positioned on the top of the chimney and spaced therefrom, the peripheral edges in close proximity to the lid as a shelter for the openings through the lid, a bail pivotally connected to the chimney.

2. In a lantern, a transparent jar, an apertured lid threadedly engaging on the jar, a chimney corrugated longitudinally engaging snugly in the aperture of the lid, a yoke pendently supported by the chimney, and a container having a tube for a wick carried by the yoke, a flange snugly engaging in the chimney and spaced from the lid, the flange functioning as a guard for the openings between the corrugations of the chimney, the said hood positioned on the top end of the chimney, the said hood having fingers as supporting and spacing means therefor from the top of said chimney, and a bail pivotally engaging with the chimney as carrying means for the lantern.

25 3. In a lantern, in combination with a jar having an apertured lid threadedly engaging thereon, a corrugated chimney snugly

engaging in the aperture of the lid, a bail attached near the upper end of the chimney, and a yoke attached to the opposite or inner end of the chimney, and a lamp carried by the yoke, a flange as a deflector attached to the chimney and spaced from the lid, and a hood carried by the top of the chimney and spaced therefrom, all being arranged to remove from the jar when the threaded lid is detached.

4. In a lantern, in combination with a transparent jar, an apertured lid threadedly engaging on the top of the jar, of a chimney engaging through the aperture in axial alignment with the jar, a plurality of openings through the top of the lid about the outside periphery of the chimney through which a downward draft is fed by the exhaust of the heated air passing outward through the chimney, a hood positioned on the top of the chimney and spaced therefrom, the peripheral edges in close proximity to the lid as a shelter for the openings through the lid, a bail pivotally connected to the chimney.

In testimony whereof I affix my signature.
JOHN J. RAMSEY.
